United States Patent Office

Des. 194,486
Patented Jan. 29, 1963

194,486

BOTTLE OR SIMILAR ARTICLE

Donald A. Hill, Arcadia, Calif., assignor to Hill Brothers Chemical Company, Industry, Calif., a corporation of California

Filed May 18, 1961, Ser. No. 65,224

Term of patent 14 years

(Cl. D58—5)

FIG. 1 is a perspective view of a bottle or similar article, showing my new design;

FIG. 2 is an enlarged side elevational view;

FIG. 3 is an enlarged front elevational view;

FIG. 4 is an enlarged rear elevational view;

FIG. 5 is an enlarged top plan view; and

FIG. 6 is an enlarged bottom plan view thereof.

The side not shown is substantially the same in appearance as the side shown.

I claim:

The ornamental design for a bottle or similar article, substantially as shown and described.
